UNITED STATES PATENT OFFICE.

WILLIAM E. FRENCH, OF CLINTWOOD, VIRGINIA.

HEATER FOR RIDING-STIRRUPS.

1,175,742.

Specification of Letters Patent.

Patented Mar. 14, 1916.

Application filed December 13, 1915. Serial No. 66,516.

To all whom it may concern:

Be it known that I, WILLIAM E. FRENCH, a citizen of the United States, residing at Clintwood, in the county of Dickenson and 5 State of Virginia, have invented certain new and useful Improvements in Heaters for Riding-Stirrups; and I do declare the following to be a full, clear, and exact description of the invention, such as will enable 10 others skilled in the art to which it appertains to make and use the same.

This invention relates generally to riding stirrups, and more particularly to improvements in heaters for riding stirrups.

15 The object of the invention is to provide a heater which may be readily attached and detached from various forms of riding stirrups, and which is simple, strong, durable and inexpensive to manufacture, efficient, 20 reliable, and well adapted to the purpose for which it is designed.

With this and other objects in view, the invention consists of certain novel features of construction, and the combination and 25 arrangement of parts which will be herein-after fully described and claimed.

In the accompanying drawings forming a part of the specification, Figure 1 is a side elevation of a device constructed in accordance with this invention, showing it applied to an ordinary riding stirrup; Fig. 2 is a rear elevation thereof; Fig. 3 is a top plan view; Fig. 4 is a vertical longitudinal sectional view through the device; Fig. 5 is a 35 sectional view taken on the line 5—5 of Fig. 4; Fig. 6 is a perspective view of the fuel drawer; and Fig. 7 is an enlarged side elevation, partly in section, of the clasp which engages the stirrup strap.

40 In the embodiment illustrated 1 represents a commonly used form of stirrup in connection with which the present invention is particularly adapted to be used, and 2 the strap for hanging the stirrup from the saddle 45 (not shown). Detachably connected to the stirrup 1 by hereinafter described means, is an outer shell or casing 3 of metal, the exterior sides of which are covered by a suitable covering 4, preferably leather. This 50 casing 3, when applied to use, extends forwardly of the stirrup 1, the front end 5 of the former being rounded as clearly shown in Fig. 3 of the drawings, and is moreover inclined rearwardly from its lower to its upper edge. The sides of the casing 3 are inclined inwardly from their lower to their

upper ends and the rear edges 6 thereof are inclined forwardly from their lower to their upper ends to form a recess 7 for receiving the stirrup 1, the sides of the casing 3 being 60 disposed adjacent the sides of the stirrup.

Threaded in an aperture in one of the sides of the casing 3 is a screw 9, the inner end of which engages the adjacent outer side of the stirrup 1, whereby said stirrup is retained between the sides of said casing. The front end 5 of this casing 3 is provided with a ring 10 to which is attached one end of a leather strap 11, the other end of the latter being provided with a suitable clasp 12 for 70 engagement with the saddle or stirrup strap 2. Disposed between the ends of the strap 11 is a suitable buckle 13 for lengthening or shortening the same, whereby said casing 75 may be adjusted to fit stirrups of various sizes.

Disposed within the outer casing 3 is an inner casing 14, the front end 15 and bottom 16 of the latter being spaced from the front end 5 and bottom 17 respectively of the former. The front end of this casing 14 is inclined rearwardly from its lower to its upper edge and the rear end is left open whereby to provide a housing to receive the front portion of the foot of the rider, the 80 sides of the casings 14 and 3 which contact with the foot of the rider being lined with a soft lining 18, preferably of felt or carpet. The other sides of the casing 14 are provided with an asbestos or any other suitable 90 heat insulating lining 19.

Disposed within the outer casing 3 between the front end 5 thereof and the front end 15 of the inner casing 14, is a shell 20, the latter having apertures 21 in its walls. 95 This shell communicates with the outside air by means of tubes 22 and additional apertures 23 in the upper side and forward end respectively thereof, the amount of opening of said tubes 22 and apertures 23 100 being regulated by rotary ventilators 24.

Slidably mounted within the shell 20 is a fuel box or drawer 25, the walls of which are provided with apertures 26 which register with the aforesaid apertures 21 and 23 105 when said drawer is positioned within said shell. The upper end of this drawer 25 is provided with a suitable knob or handle 27 whereby to facilitate its removal, when desired.

110 The rear end of the chamber 28 formed between the bottoms 16 and 17 of the casings

14 and 3 respectively, is closed by a hinged or otherwise removable closure 29 for a purpose hereinafter described.

Additional ventilators 30 are mounted opposite apertures 23' in the upper side 31 of the casing 3 to allow the heated air contained therein to escape at the control of the rider, the ventilators being opened to allow more air to escape and to reduce the amount of heat in the casing, and closed to retain the heat therein.

In operation, the device is attached to a stirrup in the hereinbefore described manner, and a block of charcoal or other suitable fuel is placed in the fuel drawer 25 and lighted. The drawer is then inserted in the shell 20 and the ventilators 24 are adjusted to obtain the proper circulation of air through the drawer 25, thence out through the aligned apertures 21 and 26 into the chamber 28 and front portion of the casing 3, and then escaping into the air through the ventilators 30, provided however, that the latter are opened. It may be thus seen that the hot air and gases circulate in the casing around the foot of the rider and keeps the same warm and comfortable in cold weather.

The ashes which fall through the apertures 21 and 26 into the chamber 28 may be cleaned out through the closure 29. This chamber 28 may, if desired, be used to store reserve fuel.

From the foregoing it may be seen that a reliable and efficient means has been provided for carrying out the objects of the invention. However, it is to be understood that various minor changes in form and proportion may be resorted to without departing from the spirit of this invention, and hence I do not wish to be limited to the construction herein shown and described other than set forth in the appended claims.

I claim:

1. A device of the character described comprising an outer casing, means for detachably connecting said outer casing to an ordinary riding stirrup, said outer casing extending forwardly of said stirrup, an inner casing disposed within said outer casing, the front end and bottom of the former being spaced from the front end and bottom respectively of the latter, a shell arranged within said outer casing between its front end and the front end of the inner casing, said shell having apertures in its walls, a fuel drawer slidably mounted in said shell, the former having apertures therein registering with those in the latter, and ventilators mounted on said outer casing and having communication with the interior of said shell to supply air to the same.

2. A device of the character described comprising an outer casing, the rear edges of the sides of which are inclined forwardly from their lower to their upper ends to form a recess for receiving an ordinary riding stirrup therein, an inner casing arranged within said outer casing for receiving the foot of the rider therein, the front end and bottom of said inner casing being spaced from the front end and bottom respectively of said outer casing, a shell arranged within said outer casing between the front end thereof and the front end of said inner casing, a fuel drawer slidable within said shell, means for ventilating said drawer, and means for detachably connecting said outer casing to said stirrup.

3. A device of the character described comprising an outer casing, the rear edges of the sides of which are inclined forwardly from their lower to their upper ends to form a recess for receiving an ordinary riding stirrup therein, the front end of said casing being rounded and inclined rearwardly from its lower to its upper edge, an inner casing arranged within said outer casing, the front end and bottom of said inner casing being spaced from the front end and bottom respectively of said outer casing, the rear end of said inner casing being open to receive the foot of the rider, a shell arranged within said outer casing between the front end thereof and the front end of said inner casing and having one of its ends open, a fuel drawer slidable within said shell, said shell and said drawer being provided with aligned apertures, means for admitting and regulating the flow of air to the interior of said outer casing, and means for detachably connecting said outer casing to the stirrup.

4. A device of the character described comprising a casing having a recess in its rear end to receive the front end of an ordinary riding stirrup, said casing extending forwardly of said stirrup, the sides of the former being disposed adjacent the sides of the latter, a screw threaded in one side of said casing and having engagement with the adjacent side of said stirrup, a strap connected at one end to the front end of said casing, means for detachably connecting the other end of said strap to the strap of said stirrup, and heating means disposed within said casing.

In testimony whereof I have hereunto set my hand in presence of two subscribing witnesses.

WILLIAM E. FRENCH.
